DESIGN FOR A PENDANT CHARM

Ernst G. Schwarz, New York, N. Y.

Application February 7, 1948, Serial No. 144,350

Term of patent 3½ years

(Cl. D45—19)

To all whom it may concern:

Be it known that I, Ernst G. Schwarz, a citizen of the United States, residing at New York city, in the county of Bronx and State of New York, have invented a new, original, and ornamental Design for a Pendant Charm, of which the following is a specification, reference being had to the accompanying drawing, forming part thereof.

In the drawing:

Fig. 1 is a face view of one side or face of a pendant charm, showing my new design;

Fig. 2 is a similar view of the reverse side and Fig. 3, a side view thereof.

The dominant feature of my design resides in the specific surface designs and their arrangement on the faces of the charm.

I claim:

The ornamental design for a pendant charm, substantially as shown and described.

ERNST G. SCHWARZ.
